DESIGN.

T. MILLER.
OIL STOVE.

No. 24,150.

Patented Mar. 26, 1895.

UNITED STATES PATENT OFFICE.

THEODORE MILLER, OF DETROIT, MICHIGAN, ASSIGNOR TO THE ART STOVE COMPANY, OF SAME PLACE.

DESIGN FOR AN OIL-STOVE.

SPECIFICATION forming part of Design No. 24,150, dated March 26, 1895.

Application filed January 17, 1895. Serial No. 535,277. Term of patent 7 years.

To all whom it may concern:

Be it known that I, THEODORE MILLER, a citizen of the United States, residing at Detroit, in the county of Wayne, State of Michigan, have invented and produced a new and original Design for Oil-Stoves, of which the following is a full, clear, and exact description, reference being had to the accompanying drawings, showing a part thereof.

10 In the drawings submitted herewith, Figure 1 is a view in perspective showing my design. Fig. 2 is a view of one of the end frames.

The leading feature of my design consists of the ornamental frame work hereinafter described.

15 A A' denote the ends of the frame which are each formed toward their respective bases with scroll work, as shown. Above the base each of the end portions forms a seat for a chamber C, the frame of each end portion rising to the rear of the chamber in two divergently curved portions a, a', having connecting bars a². In front of the said chamber the end portions of the frame are each 20 left open and without obstruction from said chamber upward. The upper ends of the curved portions a, a' are connected by a web a³ ornamented with scroll work and with diamond shaped figures, as indicated at a⁴. The 25 lower portions of the end frames constituting the base of the end frames are formed with ornamental lines as at a⁵ and a⁶ on the front and rear edges thereof and with curved lines as at a⁷. The base of each of the end frames 30 is ornamented with scroll work as shown.

B is a top surmounting the frame work on the front edge of which appears an ornamental panel G. The top is shown ornamented toward the rear thereof with open work B².

35 The chamber C is made plain of elliptical form in cross section, the ends of said chamber extending to and resting upon the end

frames. In front of said chamber and intermediate the ends A A' of the frame appear cylindrical chambers D D' visible their entire length in front of the chamber C, the upper portions of which are enlarged as indicated at d d' said chambers D D' being beaded circumferentially as indicated at d².

40 E denotes a plain shelf or platform located beneath the chambers D D', said chambers extending downward into contact with and resting upon said shelf or platform. The frame work including the shelf or platform thus supports the chambers D D' on said shelf, and the ends of the chamber C on end portions A A' thereof. The chambers D D' are surmounted by chambers F F' of cylindrical form, beaded on their exterior as shown at f f' respectively, and are provided on their 45 front faces with mica frames F² F² essentially of rectangular form, the corners of the frame however being slightly rounded. Beneath said mica frames forming light openings the chambers F F' are each provided with doors F³ or 50 ornamented with scroll work as indicated at f³.

55 The leading features of my design therefore consist of the ornamental frame work, the end portions of which are open in front to permit the ready removal of the chamber C, the chambers D D' and the chambers F F' from the frame, the ends of the chamber C resting upon the end portions of the frame, and the bases of the chambers D D' resting 60 upon the shelf E.

75 What I claim as my invention is—

The design for an oil stove, substantially as shown and described.

In testimony whereof I sign this specification in the presence of two witnesses.

THEODORE MILLER.

Witnesses:

JOHN L. MATHESON,
A. GILBERT CANBY.
